SOLE AND HEEL FORMER

William H. Doherty, Elmhurst, N. Y.

Application January 23, 1945, Serial No. 574,072

6 Claims. (Cl. 18—34)

1

This invention relates to a device to sole and heel footwear, including worn footwear, and it relates to the rehabilitation and repair thereof.

Its principal object is to provide improved means for moulding a new sole and new heel of rubber or plastic material on and affixing the same to an article of footwear whether that article be new—in which case the moulding process would take place during the course of the original manufacture of the article of footwear—or whether that article be worn, in which case the process would be one of rehabilitating or repairing.

Another object is to provide an improved sole and heel moulding means susceptible of proper adjustment into marginal conformity with an article of footwear of the character described, adapted to shape and mould the shank thereof as well as the sole and heel members thereof.

Still another object is the provision of a device of the character described which may be used in conjunction with conventional shoe holding devices commonly employed by shoe repair men in small shoe repair stores.

A still further object is the provision of a device of the character described which consists of few, simple, inexpensive parts and which, when assembled, is light in weight and convenient to handle and use.

Another object still is the provision of a device of the character described which is designed for cooperation with vulcanizing equipment of conventional types.

A preferred embodiment of the invention is shown in the accompanying drawings in which—

Fig. 1 is a plan view of the device as a whole, said device being shown applied to a conventional article of footwear;

Fig. 2 is a transverse section of said device on the line 2—2 of Fig. 1;

Fig. 3 is a transverse section of said device on the line 3—3 of Fig. 1;

Fig. 4 is a fragmentary side view of the device;

Fig. 5 is a fragmentary detailed sectional view on the line 5—5 of Fig. 1;

Fig. 6 is a perspective view of the moulding band of said device, and;

Fig. 7 is a perspective view of a unitary sole, shank and heel member formed by said device.

Referring now to Fig. 6, it will be seen that the moulding member of the device comprises a unitary strip or band 10 of relatively flexible, relatively resilient material, such as spring metal. Band 10 is shown shaped to the marginal lines of conventional heel, shank and sole members

2

of a conventional article of footwear. It is clear from the drawings that band 10 is of substantially uniform thickness throughout but its width varies from a relatively wide heel portion which tapers gently at the shank portion to a relatively narrow sole portion. Band 10 is provided at predetermined intervals with small holes 11 whose function will hereafter appear.

It will be noted that there is overlapping of the end portions of said band at the shank and that one end thereof curls outwardly at that point to form approximately two-thirds of a circle. The very tip end 12 of said circular portion 13 is bent over at right angles thereto.

Referring now to Fig. 1, it becomes apparent that a ratchet mechanism 14 is disposed in the circular space formed by said circular portion 13 and that said ratchet mechanism engages tip 12 thereof. Ratchet mechanism 14 comprises a rotatable wheel 15 to which is affixed a ratchet wheel 16, which ratchet wheel is engaged by a fixed pawl 17.

A slot or notch in wheel 15 accommodates the bent tip 12 of band 10. A square hole 18 in said wheel 15 and ratchet wheel 16 accommodates a crank or key member which is not shown. It is clear that rotation of wheel 15 and ratchet wheel 16 in a counter clockwise direction as viewed in Fig. 1 causes a drawing together of band 10 and a consequent reduction of the space encompassed and defined by said band 10. This will become clear as the specification proceeds.

Referring now to Fig. 1, it will be seen that when the band 10 is placed in operative position upon conventional article of footwear 20, nails or tacks 21 inserted through holes 11 in said band affix the band to the article of footwear and more particularly to the welt 22 and heel 23 portions thereof. Fig. 5 will show that

a substantially L-shaped member 24 having a wedge shaped foot is mounted on each said nail or tack 21 to brace and erectly support band 10 during the moulding operation. The wedge shaped foot is wedged by means of said nails 21

into the space between welt 22 and upper 25 adjacent the point where said welt, said upper and the inner sole 26 are respectively affixed to each other. At the inner end of the heel section is a transverse band 27 which extends at both ends to band 10. Between said transverse band and the sole portion proper is a shank core 30 which occupies the space corresponding to the space formed beneath the shank of a conventional shoe when that shoe is placed upon a flat surface. The shank core comprises a pair of

spaced longitudinally extending members 31 and 32 respectively which are mounted between a pair of spaced upper shank plates 33 and 33a, respectively, and a lower shank plate 34. Upper plates 33 and 33a have a pair of side walls 35 and 36, respectively, with inwardly bent end portions 37 and 38, respectively, which correspond to the wedge shaped foot portions of bracing members 24 and perform the same function therewith. Lower shank plate 34 is provided with a rear wall 39 which has a forwardly bent upper end portion 40. The forward end 41 of lower shank plate 34 is bent backward facing bent portion 40. It thus appears that the shank members 31 and 32 are held in place by upper and lower plates 33 and 33a, and 34, respectively, and their walls 35 and 36, and 39, respectively.

Referring now to Fig. 3, it will be noted that a transverse screw member 45 extends through apertures 46 and 47 in side walls 35 and 36, respectively, apertures 48 and 49 in the band member 10 and loose threaded apertures 50 and 51, respectively in cores 31 and 32. It will be noted too that screw member 45 is rotatably fixed at its center portion in a bearing 52 which is mounted on lower plate 34. Said bearing permits of rotation of screw 45 on its own axis but prevents axial displacement of said screw relative to said bearing. It will be noted also that screw 45 is provided on one side of bearing 52 with right screw threads and on the other side with left screw threads. Core members 31 and 32, respectively, are provided with corresponding screw threads so that when screw 45 is caused to rotate on its axis, core portions 31 and 32 will move in opposite directions either toward or away from one another.

Nuts 60 and 61, respectively, are mounted on the opposite ends of screw 45 immediately adjacent side walls 35 and 36, respectively. Nut 61 is provided with a square key receiving aperture 62. Screw 45 has affixed to the end opposite the end on which nut 61 is mounted a knurled knob 63.

Nuts 60 and 61, respectively, are used to tighten the contact between walls 35 and 36 on the one hand and band 10 on the other and band 10 on the one hand and core members 31 and 32 on the other.

Referring again to Fig. 1, it will be seen that the foot portions 37 and 38, respectively, of walls 35 and 36 are provided with serrated edges which are intended, when the band is drawn together as herein described, to prevent creeping. It will also be noted in Fig. 1 that upper plate 33 is provided with a slotted ear 65 which accommodates—see Fig. 2—a screw member 66 having eccentric wedge shaped head 67 which performs the same function as the feet of braces 24 and the inwardly turned wedge members 37 and 38 of walls 35 and 36, respectively. This slot arrangement permits of lateral movement of plate 33. Plate 33a also has an ear 68 which is substantially as large as the cross-sectional dimensions of the ratchet mechanism 14. Fig. 2 will show that the ratchet mechanism is rotatably carried by said ear 68. The pawl 17 of said ratchet mechanism which has hereinabove been described as a fixedly mounted pawl, is affixed in the usual manner, as by pin 69 to said ear 68.

It is not difficult to understand how the device above described may be used. It is mounted on the article of footwear by means of nails 21 as above described. Screw 45 and nuts 60 and 61 are manipulated to adjust the positions of core

members 31 and 32 with respect to each other and the degree of pressure contact between walls 35 and 36 and band 10 and said core members 31 and 32. Ratchet mechanism 14 is now operated in the usual way thereby drawing the curled end of band 10 around it and urging said band into marginal conformity with the sole and heel members of said article of footwear. The device is now ready for use. A plastic material or rubber is poured into the mould and the operation continues from this point on in the conventional manner. After the plastic material is set, the device is removed and the end product may be seen in Fig. 7 affixed, however, to the shoe. It is clear from Fig. 7 that what has been produced is a unitary member having a heel portion 70, a shank portion 71 integral therewith, and a sole portion 72 integral with said shank portion. The sole and heel portions of the unitary member shown in Fig. 7 are provided with depressed portions (or raised portions) 73 which are formed therein in the usual manner by means of a suitable mould or otherwise.

The device above described is but a preferred embodiment of the invention and changes may be incorporated therein without departing from the basic principles thereof. These basic principles form the subject matter of the claims here-to appended.

I claim:

1. A device for moulding the sole, heel and shank of an article of footwear, said device comprising a unitary flexible band, said band having two overlapping ends, a shank core in said band, adjusting means cooperating with said shank core for pressing said band into marginal conformity with the shank, additional adjusting means for drawing said band into marginal conformity with the sole and heel by pulling one end of said band until the band is contracted to appropriate size and shape, and means to demountably attach said band to said article of footwear.

2. A device for moulding the sole, heel and shank of an article of footwear, said device comprising a unitary flexible band, said band having two overlapping ends, a laterally adjustable shank core in said band, adjustable screw means cooperating with said shank core for pressing said band into marginal conformity with the shank, ratchet means for drawing said band into marginal conformity with the sole and heel by pulling one end of said band until the band is contracted to appropriate size and shape, and means for demountably attaching said band to said article of footwear.

3. A device for moulding the sole, heel and shank of an article of footwear, said device comprising a unitary flexible band having two overlapping ends, said band being adapted to conform to the marginal outlines of said sole, heel and shank, said band being relatively wide at the heel, tapering at the shank and being relatively narrow at the sole, a laterally adjustable shank core positioned in said band, screw means cooperating with said shank core for pressing said band into marginal conformity with the shank, ratchet means for drawing said band into marginal conformity with the sole and heel by pulling one end of said band until the band is contracted to appropriate size and shape, and means for demountably attaching said band to said article of footwear.

4. A device for moulding the sole, heel and shank of an article of footwear, said device comprising a unitary, relatively flexible band having

two overlapping ends, said band being adapted to conform to the marginal outlines of said sole, heel and shank, said band being relatively wide at the heel, tapering at the shank and being relatively narrow at the sole, a laterally adjustable shank core, screw means for pressing the shank portions of said band against and in marginal conformity with said shank core, a ratchet mechanism engaging one end of said band and drawing said band into marginal conformity with the heel and sole, and nail means for demountably attaching said band to said article of footwear.

5. A device for moulding the sole, heel and shank of an article of footwear, said device comprising a unitary, relatively flexible band having overlapping ends, said band being adapted to conform to the marginal outlines of said sole, heel and shank, said band being relatively wide at the heel, tapering at the shank and being relatively narrow at the sole, a laterally adjustable shank core, screw means for pressing the shank portions of said band against and in marginal conformity with said shank core, a ratchet mechanism engaging one end of said band and drawing said band into marginal conformity with the heel and sole, and nail means for demountably

attaching said band to said article of footwear, said shank core comprising a pair of longitudinal members which are transversely adjustable both with respect to each other and with respect to the article of footwear.

6. A device for moulding the sole, heel and shank of an article of footwear, said device comprising a unitary flexible band having overlapping ends, said band being adapted to conform to the marginal outlines of said sole, heel and shank, said band tapering at the shank from a relatively wide heel portion to a relatively narrow sole portion, a laterally adjustable shank core against which one of the ends of said band is pressure-held, a ratchet mechanism engaging the other end of said band and drawing said band into marginal conformity with the heel and sole, screw means for pressing the shank portions of said band against and in marginal conformity with said shank core, and tacking means for demountably attaching said band to said article of footwear, said shank core comprising a pair of longitudinally extending members which are transversely adjustable both with respect to each other and with respect to the article of footwear.

WILLIAM H. DOHERTY.
